MULTIPLE UNIT INSERTION MACHINE FOR BLASTING INITIATOR WIRES

Daniel D. Huyett, Wilmington, Del., assignor to Atlas Powder Company, Wilmington, Del., a corporation of Delaware

Application May 9, 1952, Serial No. 286,958

23 Claims. (Cl. 86—1)

The present invention relates to new and useful improvements in wire insertion apparatus and more particularly to new and useful improvements in apparatus adapted to insert a plurality of pairs of wires into a like number of resilient rubber plugs or the like.

The present invention is particularly adapted to insert a plurality of pairs of wires into a like number of resilient rubber plugs or the like, for example, preformed plug closures which, in turn, are inserted into loaded detonator shells as shown and described in my co-pending application, Serial No. 249,298, filed October 2, 1951. In the manufacture of blasting initiators, a pair of wires is inserted through a preformed plug closure which then has an ignition device or match secured thereto and is inserted into the open end of a loaded detonator shell. Prior to the present invention, a single pair of wires has usually been inserted into a preformed plug closure individually. This increases considerably the amount of time and labor needed for the manufacture of blasting initiators or the like and makes it impossible to use modern production line methods in the manufacture of such articles.

With the foregoing in mind, the principal object of the present invention is to provide novel apparatus which is operable to insert simultaneously a plurality of pairs of wires into a plurality of rubber plugs such as preformed plug closures for electric blasting initiators and which may be constituted as a single station in a production line for the manufacture of electric blasting caps or initiators and the like.

A further object of the present invention is to provide a novel apparatus of the stated character which greatly improves upon prior wire insertion methods and apparatus.

These and other objects of the present invention and the various features and details of the operation and construction thereof are hereinafter more fully set forth and described with reference to the accompanying drawings in which:

Fig. 45 is a perspective view of a plug with needles and tubes inserted therethrough illustrating the distortion which takes place in the plug support; and,

Fig. 46 is a schematic diagram illustrating the elec-

tric and pneumatic operating controls for the wire insertion machine.

The present invention consists essentially of providing a machine operable to simultaneously insert a plurality of pairs of electric wires into a corresponding plurality of preformed resilient plugs. Two operators are required to operate this machine. The first operator positions a tray or jig which carries the wires on a feed table and initiates actuation of the machine while the second operator inserts a plug holder, supporting the preformed resilient plugs, in the machine. Slidably mounted interiorly of the machine for vertical movement between predetermined limit positions is a transfer plate on which the plug holders are placed. Immediately above the transfer plate is a pair of latches which support the plug holders. During the operation of the machine, the transfer plate is raised and then lowered, thereby transferring the plug holder from the transfer plate to the latches.

Extending transversely of the wire insertion machine of the present invention is a split funnel plate having a plurality of openings therethrough. The wires are positioned at one side of the split funnel plate in axial alignment with the openings therein while the plugs are supported by the latches at the opposite side of the split funnel plate in alignment with the pairs of wires. At the beginning of operation of the machine, when the operators are inserting the wires and plugs into the machine, a set of plugs is positioned in alignment with the openings of the split funnel plate and each plug has a pair of tubes inserted therethrough. When the wires are properly positioned on the feed table of the machine and a plug holder positioned on the transfer plate, the operator may close a switch, thereby actuating the feed table in the forward direction to insert the wires through the split funnel plate and into the tubes. After the wires are properly inserted into the tubes, the operator of the machine may then close a second switch which initiates actuation of a cam shaft carrying a plurality of cams operable to complete the wire insertion operation.

The first step in the wire insertion operation is to withdraw the tubes from the plugs thereby transferring the plugs from the tubes to the wires. The split funnel plate is then opened and the feed table retracted to withdraw the plugs from the plug holder and through the split funnel plate. The split funnel plate then closes and the transfer plate is raised and lowered to position another plug holder carrying a plurality of plugs in alignment with the openings in the split funnel plate. At the same time, the first operator of the machine may replace the tray or jig supporting the wire and plug assemblies on the feed table with a second tray or jig supporting a second plurality of wires.

A plurality of needles are positioned on the same side of the split funnel plate as the plugs co-axially with the tubes. The cam shaft operates to force the needles forward inserting them through the plugs. After the needles have pierced the plugs, the tubes are actuated in the forward direction thereby inserting the tubes through the plugs, and the needles are then retracted. During this phase of the operation, the second operator of the machine may position a plug holder carrying a plurality of plugs onto the transfer plate. The machine is automatically stopped in this position and is prepared for a second insertion operation.

The present invention is particularly designed to be used as a single station in a production line for the manufacture of electric blasting caps or the like. To this end, a wire jig or carrier designated generally as 10 (see Figs. 31, 32 and 33) is provided to support wires 11 on the ends of which the electric blasting caps or initiators are placed. The wire jig is the subject of a co-pending application, Serial No. 254,178, filed October 31, 1951, now Patent 2,759,251, dated Aug. 21, 1956. The initial operation in the manufacture of blasting caps is to place the wires 11 in the wire jig 10 and the wire jig

is then conveyed to different stations on the production line where the various component parts of the electric blasting caps or initiators are assembled. In the present instance, the wires 11 have preformed rubber plugs (see Fig. 29) placed thereon as more fully described hereinafter. It will be understood however that the wire jig 10 is not a necessary part of the present invention, but only a convenient accessory which allows the present invention to be more easily used in a production line.

With reference to Figs. 31, 32 and 33 of the drawings, the wire carrier or jig 10 comprises a tray portion 12 on which spools or bundles of wires may be placed. The wires extend from the spool or bundles through a clamping member 13 as illustrated in Fig. 33, which securely grips the wires 11 between a pair of rubber gaskets 14 and prevents displacement of the wires with respect to the wire jig. Positioned at the forward end of the wire jig 10 is a displaceable guide 15 which is telescopically mounted in the side wall portions of the wire jig and normally urged to a forward limit position by means of springs 16 as illustrated in Fig. 32. Extending transversely of the wire tray 10 are front and rear skids 22 and 23, respectively, which allow the tray to be inserted and positioned on the wire insertion machine as more fully described hereinafter. The extreme forward limit position of the displaceable guide 15 is determined by means of a lug 17, which extends downwardly from the rear surface of the side arms of the displaceable guide 15 and is normally urged against the rear skid 23 by means of the above-mentioned springs 16, 16.

The present invention is particularly designed to simultaneously insert a plurality of pairs of wires into a corresponding plurality of preformed rubber plugs or the like. To this end, a jig supporting a plurality of wires and a plug holder carrying the plugs are inserted into the wire insertion machine and positioned in axial alignment with each other. The plugs are then pierced and have tubes inserted therethrough in which the wires are placed. Subsequently, the tubes are withdrawn from the plugs leaving the plugs in their proper position on the wires. The wires and plugs are then withdrawn from the wire insertion machine and the machine is prepared for another inserting operation.

With reference to Fig. 2, the wire jig 10 supporting a plurality of wires 11 is fed to the plugging machine at the forward left hand side thereof as indicated at A. The wire jig 10 is carried by a conveyor (not shown) and is positioned on a feed table 42 by the operator of the machine and securely locked thereon, as more fully described hereinafter, during the inserting operation. A second conveyor (not shown) positioned at the opposite side of the feed table 42 removes the wire jig from the wire insertion machine after the insertion operation. A plurality of preformed resilient plugs 43 are carried by a plug holder 44, see Fig. 30, which is inserted into the wire insertion machine at the central right hand side thereof as indicated at B in Fig. 2. The plugs are then pierced and the wires inserted therein as more fully described hereinafter.

A plurality of pairs of wires are carried by the jig 10 and are adapted to be projected outwardly from the forward edge thereof. Extending transversely of the wire insertion machine and mounted for limited longitudinal movement with respect thereto is the feed table 42 which supports the wire jig 10 during the entire wire insertion operation. As shown in Fig. 8, the feed table 42 has a transverse width approximately equal to the distance between the front and rear skids 22 and 23 of the wire jig 10 and the feed conveyor (not shown) is adapted to position the wire jig 10 in such a manner with respect to the feed table 42 so that the front and rear skids 22 and 23 of the wire jig 10 are positioned at respectively opposite sides of the feed table 42 when the wire jig 10 is slid onto the feed table 42. A plurality of rollers 45 are disposed along each side of the feed table 42 as illus-

trated in Figs. 2 and 8, and engage the skids 22 and 23 to permit the wire jig 10 to be easily placed on the feed table.

When the operator of the machine slides a jig onto the feed table 42, it engages a second jig which is in the position shown in broken lines in Fig. 2, carrying the completed wire and plug assemblies and forces the second jig off of the feed table onto a conveyor (not shown). As the second jig is removed from the feed table, it passes over a roller 46 carried on the upper end of an arm 47 pivotally mounted to the wire insertion machine as indicated at 48 in Figs. 1, 4 and 12. The arm 47 has a downwardly depending portion 51 thereon operable to momentarily close a switch 52 when the jig 10 passes over a roller 46.

Actuation of the switch 52 admits air under pressure to the right hand end of an air cylinder 53 as viewed in Figs. 8, 9 and 10. Admittance of air to the air cylinder 53 moves a locking plate 54 forward. The locking plate 54 has a forwardly extending projection 55 formed integral therewith which constitutes a stop element whereby the incoming wire jig is accurately positioned laterally with respect to the feed table 42. The projection 55 advances under actuation of the air cylinder 53 to intercept the downwardly projecting lug 17 of the wire tray thereby arresting lateral movement of the tray with respect to the feed table 42. The projection 55 comes to rest against the side of the rear skid element 23 and the contained pressure of the cylinder 53 is effective to lock the wire tray securely against the table 42. A resiliently biased latch member 57 is pivotally mounted on the underside of the table 42 at the feed end thereof and is actuatable to be biased outwardly into engagement with the side of the rear skid 23. Fig. 25 clearly illustrates this positioning and locking arrangement of the locking plate 54 and latch member 57. By this construction, after a wire jig is slid onto the feed table of the wire insertion machine, the locking plate 54 and latch 57 prevent any displacement laterally of the jig on the feed table 42.

The feed table 42 is carried on a frame 60 as shown in Figs. 2, 8 and 12, which in turn is mounted for longitudinal movement to allow the feed table and wire jig to be brought forward, thereby inserting the wires into the plugs which are positioned in axial alignment with the wires as more fully described hereinafter. To this end, a pair of spaced parallel tracks 61 are provided on the wire insertion machine extending longitudinally thereof. The tracks 61 have grooves 62 on their inner surface adapted to receive tongues 63 extending outwardly from the sides of the feed table frame 60, thereby permitting relative longitudinal movement of the feed table 42 with respect to the wire insertion machine.

The locking plate 54 is secured to a locking plate frame 64, which, in turn, is mounted for limited longitudinal movement with respect to the feed table 42 to allow the locking plate to be brought up against the rear surface of the wire jig 10. A pair of tubular slides 65 are secured to the feed table frame 60 as indicated in Figs. 2 and 8, and the cross members 64a of the locking plate frame 64 are slidably mounted on the slides 65. The air cylinder 53 is secured to the locking plate frame 64 and has the forward end of its piston rod 66 secured to the feed table frame 60 as indicated at 67, thus admittance of air to the right hand end of the air cylinder 53 will bring the locking plate forward to engage the lug 17 on the wire tray 10. Depending downwardly from the lower surface of the locking plate frame 64 is a bracket 68, as shown in Fig. 8, which carries a roller 69 thereon operable to actuate a switch 72. The switch 72 is a normally closed switch and is held open by means of the roller 69 when the locking plate 54 and the feed table 42 are in their extreme rearward position as illustrated in Fig. 8.

As shown in Figs. 8, 9 and 10, actuation of the feed table frame 60 and the feed table 42 is effected by a

double acting air cylinder 73 which is secured to the frame of the wire insertion machine and has its piston rod 74 secured to the feed table frame 60 as indicated at 75. Admittance of air to the left hand end of the air cylinder 73 will bring the feed table 42 toward the central portion of the plugging machine. The operating stroke of the air cylinder 73 is initiated by a manually operated switch 76 which is in series with the previously mentioned switch 72 and a third switch 91, more fully described herein-10 after, which is closed when the plugs and plug holder are in their proper position. As the tray 10 is brought forward by means of the air cylinder 73, index holes 77, 77 in the confronting face of the displaceable guide 15 carried by the jig 10 are brought into registering engagement with a pair of pins 78, 78 (see Figs. 4, 8 and 15) to properly position the forward end of the wire jig laterally of the machine. As previously mentioned, the lug 17 which is engaged by the locking plate 54 during the operating stroke of the feed table 42 is secured to the displaceable guide 15 and thus the locking plate 54 and the air cylinder 53 serve to provide the necessary force to force the guide 15 onto the pins 78, 78. After the guide 15 engages the pins 78, the air cylinder 73 continues its operating stroke for a predetermined distance 20 in order to insert the wires into the plugs. During this time, the locking plate 54 and displaceable guide 15 remain stationary while the feed table 42 is moved forward to a position as indicated in Fig. 10. Thus, the wires carried by the jig 10 are projected forward with 25 respect to the displaceable guide and extend outward from the forward face thereof as shown in Figs. 34 and 35.

In accordance with the present invention, the plug holders 44 which carry the plugs 43 are positioned on a feed table 81 as illustrated in Figs. 4a, 5 and 27. The 30 plug holders, as shown in Fig. 30, have a plurality of clover-shaped openings 82 therein in which the plugs are inserted. The clover-shaped openings allow the plug to expand when the needles and tubes are inserted therethrough as more fully described hereinafter. Extending 35 longitudinally of the feed table 81 is a guide rail 83 which carries a push-block 84. The push-block 84 is adapted to bear against the end of a plug holder 44 which in turn is positioned between the guide rail 83 and a face plate 85 on the feed table, as shown in Fig. 27, and 40 insert the same through an opening 86 into the wire insertion machine.

Extending transversely of the wire insertion machine in axial alignment with the opening 86, is a transfer or lifting plate 88 on which the plug holders 44 are placed 45 after insertion into the machine as illustrated in Figs. 6 and 8. Upon full insertion of a holder 44 into the wire insertion machine and onto the transfer plate 88, a micro-switch 91 is closed by means of a plunger 92 which extends into the path of the plug holder. As a plug holder 50 is inserted into the machine, it depresses the plunger 92, thereby closing the switch 91. The switch 91 is in series with the previous mentioned micro-switch 72 and the manually operated switch 76, and when these three 55 switches are closed, the feed table 42 will be brought forward.

As previously mentioned, and more fully described herein-60 after, at the end of an insertion operation, a plug holder 44 carrying plugs 43 is positioned in axial alignment with the wires supported on the feed table 42 and 65 the plug is prepared for the reception of wires. Thus, after a holder carrying a plurality of plugs 43 is inserted into the machine and a jig 10 supporting the wires 11 is placed on the feed table 42, closing the manually operated switch 76 will actuate the feed table 42 and insert the 70 wires into the plugs. A pause is provided in the operation of the plugging machine at this point in order to allow the operator of the machine to make an inspection and determine whether or not the wires are properly inserted in the plugs. If the wires are not properly 75 inserted in the plugs, the operator of the machine may

close the manually operated switch 94 positioned on the forward end of the machine next to the switch 76, as illustrated in Fig. 4. Closing the switch 94 will admit air to the left hand end of the air cylinder 73, thereby retracting the feed table 42 to permit the operator of the machine to properly position the wires. The operator of the machine may then close the manually operated switch 76 inserting the wires into the plugs as previously described.

In order to complete operation of the machine, the operator closes the manually operated switch 95 which is also positioned at the forward end of the machine as shown in Fig. 4. This allows a cam shaft 96 carrying a plurality of cams to make one complete revolution, thereby completing operation of the wire insertion machine as set forth in detail herebelow. The manually operated switch 95 which actuates the cam shaft 96 is in series with a normally open switch 97, more fully described hereinafter, and when the switches 95 and 97 are both closed the cam shaft 96 may be rotated. With reference to Figs. 8 and 10, the switch 97 is secured to the frame of the wire insertion machine beneath the feed table 42 and is adapted to be engaged and maintained in a closed position by a finger 98 which depends downwardly from the feed table frame 60. As the feed table advances, the finger 98 engages the switch 97 and closes the same. By this construction, rotation of the cam shaft 96 is effectively prevented until the feed table 42 is in its extreme forward limit position.

With reference to Figs. 2a and 3 of the drawings, reference numeral 100 designates generally an electric motor which drives the cam shaft 96. Fixedly secured to the drive shaft of the motor 100 is a pulley 101 which drives a second pulley 102 by means of a plurality of V-belts or the like 103. The pulley 102 is rotatably mounted on the high speed shaft 104 of a gear reducer 105 and is adapted to be interlocked therewith by means of a clutch operating member 106 as more fully described hereinafter. The cam shaft 96 is secured to the low speed shaft 107 of the gear reducer 105 by means of a coupling 108.

The high speed shaft 104 is provided with a brake comprising a brake drum 111 rotatably mounted thereon and adapted normally to be held stationary by means of a brake band 112 which encircles the brake drum 111 and has both its ends adjustably secured to a cross frame member 113 on the frame of the wire insertion machine as indicated in Fig. 26.

Slidably mounted on the high speed shaft 104 centrally of the pulley 102 and the brake drum 111 is the clutch operating member 106. The member 106 is splined to the shaft 104 and is rotatable therewith. A double acting air cylinder 114 controlled by the manually operated switch 95 is provided to actuate the clutch operating member 106 longitudinally along the high speed shaft 104 to engage either the pulley 102 or the brake drum 111 with the shaft 104 in order to rotate or stop rotation of the cam shaft 96 as more fully described hereinafter. The air cylinder 114 is interconnected with the clutch operating member 106 by means of shift rod 115 which has one end pivotally secured to the end of the piston rod 116 of the air cylinder 114 and its other end pivotally mounted to the framework of the wire insertion machine as indicated at 117 in Figs. 2a and 3. The shift rod 115 engages the clutch operating member 106 so that actuation of the air cylinder 114 operates to move the clutch operating member longitudinally of the shaft 104.

Secured to the side of the pulley 102 nearest the clutch operating member 106 is a friction disk type clutch 122 which has one set of disks keyed to the shaft 104 and the other set of disks mounted in a housing 123 secured to the pulley 102. Application of pressure to the disks of the clutch 122 by the clutch operating mem-

ber 106 drivably connects the pulley 102 with the shaft 104. Alternatively, when the clutch operating member 106 is removed from pressure applying relationship with the disks of the clutch 122, the pulley 102 is freely rotatable with respect to the shaft 104.

A friction disk type clutch 125 similar to the clutch 122 is secured to the side of the brake drum 111 nearest the clutch operating member 106. The clutch 125 has one set of disks secured to the shaft 104 while the other set of disks is carried by a housing 126 secured to the brake drum 111. The clutch 125 operates in a manner similar to the clutch 122 so that when the clutch operating member 106 is actuated to the left with respect to Fig. 3, pressure is applied to the disks of the clutch 125. The brake drum 111 and the shaft 104 are then interlocked thereby stopping rotation of the shaft 104 and also of the cam shaft 96. In a like manner, when the clutch operating member 106 is removed from pressure applying relationship with the disks of the clutch 125, the shaft 104 is rotatable with respect to the brake drum 111. By this construction, when the clutch operating member 106 is in its extreme right hand position, the pulley 102 has a driving connection with the high speed shaft 104 of the gear reducer 105 and the motor 100 operates to drive the cam shaft 96. Actuation of the clutch operating member 106 to its other extreme position as indicated in Fig. 3 disengages the pulley 102 and the shaft 104 and, at the same time, interlocks the brake drum 111 and the shaft 104, thereby effectively stopping rotation of the cam shaft 96. The manually operated switch 95 is operable to admit air to the left hand end of the air cylinder 114 (with respect to Fig. 3), thereby moving the clutch operating member 106 to the right to cause rotation of the cam shaft 96. A micro-switch 239 more fully described hereinafter, operates to admit air to the right hand end (with respect to Fig. 3) of the air cylinder 114, thereby stopping rotation of the cam shaft 96 as described above.

As previously mentioned, at the end of a completed cycle of operation, the plugs 43 are prepared for the reception of wires. To this end, a pair of expander tubes 130 are inserted through each of the plugs as illustrated in Figs. 34 and 42, and the cam shaft 96 is stopped so that the cams are in the positions as illustrated in Figs. 20 to 24, inclusive, of the drawings. Upon starting rotation of the cam shaft 96 the tubes 130 are retracted from the plugs 43, thereby transferring the plugs from the tubes to the wires 11 as shown in Fig. 35. A backer-up plate 131 through which the tubes 130 pass bears against the rear of the plugs and prevents relative rearward movement of the plugs 43 during retraction of the tubes 130.

Operation of the tubes 130 is effected by a cam 132 formed, for example, as illustrated in Fig. 20. The cam 132 has a cam track 133 therein which engages a cam follower 134 on an arm 135. As shown in Figs. 1 and 8a, the arm 135 is secured to a shaft 136 extending transversely of the plugging machine. Depending upwardly from the shaft 136 are two pairs of ears or lugs 137 which engage a pair of eyes 138 adjustably secured to a tube crosshead 139 by means of turnbuckles 140, 140, as illustrated in Fig. 2.

Extending longitudinally of the wire insertion machine and depending inwardly from the side walls thereof are a pair of supports 143 which carry slides 144 thereon on which the tube crosshead 139 is slidably mounted, as shown in Figs. 7 and 11. As the cam 132 starts rotating, the lower end of the arm 135 is moved to the left with respect to Fig. 1, thereby pivoting the arm 135 in a clockwise direction about the shaft 136 and pulling the tube crosshead 139 to the right. Positioned at the forward end of the tube crosshead 139 and fixedly secured thereto is a plate 145 which has a plurality of slots 146 in its upper surface (see Figs. 8, 18 and 38). Each slot is adapted to receive a supporting block 147 which carries a pair of tubes 130. As illustrated in Fig. 18, the sup-

porting blocks 147 have grooves 149 along each side thereof adapted to be engaged by the plate 145 to prevent relative horizontal movement of the supporting blocks 147 with respect to the plate 145. A cap-plate 152 is removably secured to the plate 145 adjacent the upper surface of the supporting blocks 147 to prevent relative vertical movement of the plugs 147 with respect to the plate 145. A pair of spaced parallel openings extend through the plugs 147 longitudinally of the wire insertion machine in which the tubes 130 are secured, for example, by soldering. By this construction, as the tube cross-head 139 is retracted by means of the cam 132, the tubes 130 are withdrawn from the plugs.

As previously mentioned, the split funnel plate 155 extends transversely of the wire insertion machine and the wires and plugs are positioned at respectively opposite sides of the split funnel plate. The split funnel plate 155 consists of corresponding left and right halves 153 and 154, respectively, as shown in Figs. 13, 15 and 17. During insertion of the wires 11 into the tubes 130, the split funnel plate 155 is in the position shown in Fig. 17 to guide the wires into the tubes. Simultaneously, upon withdrawal of the tubes 130 from the plugs 43, the left and right halves 153 and 154, respectively, of the split funnel plate 155 are separated from each other to the position shown in Fig. 17a, thereby providing room between the halves 153 and 154, respectively, of the split funnel plate 155 between which the plugs may be withdrawn. The halves 153 and 154, respectively, of the split funnel plate 155 are carried by lower and upper cross-bars 156 and 157, respectively, which are slidably mounted for limited longitudinal movement with respect to each other as more fully described hereinafter.

With reference to Figs. 13 and 14, the lower cross-bar 156 is supported by a pair of wear-plates 158, 158, secured to the side frame of the wire insertion machine. The upper cross-bar 157 is slidably mounted on the lower cross-bar as shown in Fig. 14 and is maintained in position by a pair of wear-plates 162, 162 adapted to bear against the upper surface of the cross-bar 157.

A pair of push-rods 163 and 164 are secured to the cross-bars 156 and 157, respectively, as shown in Fig. 13. The push-rods in turn are adjustably secured to the opposite ends of a yoke 165 fixedly mounted on a rotatable shaft 166. By this construction, rotation of the shaft 166 in a clockwise direction will cause the upper cross-bar 157 to move to the right with respect to Fig. 13 and the lower cross-bar 156 to move to the left, thereby separating the respective halves of the split funnel plate 155. To accomplish this, a cam 168 formed, for example, as illustrated in Fig. 24 is secured to the cam shaft 96. The cam 168 has a cam track 169 therein operable to engage a cam follower 172 carried centrally on an arm 173.

With reference to Fig. 1, the arm 173 is pivotally secured at its extreme left hand end to the housing of the wire insertion machine, for example, as indicated at 174 and extends outwardly beyond the rear of the wire insertion machine. The outer end of the arm 173 has an opening 173a therein, as shown in Fig. 7, through which a connecting rod 175 passes. The connecting rod 175 extends upwardly from the arm 173 and is pivotally secured to the midpoint of a toggle mechanism 176 which consists of a pair of links pivotally secured together, as illustrated in Fig. 16. One of the links of the toggle mechanism 176 is pivotally secured to a bracket 176a mounted on the frame of the machine while the other link of the toggle mechanism is pivotally secured to an arm 166a which projects upwardly from the aforementioned rock shaft 166. By this construction rotation of the cam 168 will pivot the arm 173 in a clockwise direction with respect to Fig. 1 about its pivot point 174 and pull the connecting link 175 downward. Downward movement of the connecting link 175 will in turn rotate the rock shaft 166 in a clockwise direction with respect to Fig. 13 thereby opening the split funnel plate as previously described.

In a like manner, further rotation of the cam 168 will cause the connecting link 175 to be raised thereby closing the split funnel plate.

In accordance with the present invention, means are provided to prevent undue pressure from being applied to the split funnel plate when it is being closed, thereby preventing excess strain on the split funnel plate if an object should be caught between the two halves during the closing thereof. To accomplish this a compression spring 177 is provided through which the force due to the upward movement of the arm 173 is transmitted to the connecting link 175. The compression spring 177 encircles the link 175 and is held captive between an adjusting nut 177a at its upper end and a washer 177b at its lower end which engages the arm 173 (see Figs. 7 and 16). The adjusting nut 177a is threaded on the connecting link to permit the force exerted by the compression spring to be varied, while the washer 177b is freely mounted on the connecting link 175 for relative axial movement therewith. By this construction if an object is caught in the split funnel plate when it is being closed the strain exerted upon the split funnel plate is limited by the force required to compress the spring 177.

Mechanism is provided in the present invention to stop operation of the wire insertion machine if the split funnel plate is not fully closed upon upward movement of the connecting link 175. This is accomplished by a pair of series connected switches 178 and 179 (see Figs. 7 and 16) which will cause the clutch to be disengaged if a circuit is completed through them, as more fully described hereinafter. The switch 178 is a normally closed switch adapted to be opened by an operating lever 178a which projects outwardly from the end of the toggle mechanism. Complete upward movement of the connecting link 175 will cause the toggle mechanism to assume the position shown in full lines in Fig. 16 thereby causing the operating lever 178a to engage and open the switch 178. The switch 179 is a normally open switch adapted to be closed upon engagement with an operating lever 179a. The operating lever 179a is fixedly secured to the outer end of the arm 173 and engages the switch 179 upon completion of the clockwise rotation, with respect to Fig. 1, of the lever 173. By this construction if the connecting link 175 is prevented from moving from its upward limit position, for example by an object caught in the split funnel plate, the switch 178 will remain closed and the switch 179 will be closed by the operating lever 179a thereby completing a circuit which causes disengagement of the clutch, as more fully described hereinafter. In a like manner, if the connecting link is permitted to move to its upper limit position by the operating lever 178a the switch 178 will be opened prior to closing of the switch 179 by the lever 179a thereby preventing completion of a circuit through the two switches.

Immediately following the opening of the split funnel plate 155, a pair of ejector rods 181, 181, as shown in Fig. 2, advance and force the wire jig 10 rearwardly with respect to the split funnel plates, thereby withdrawing the wires and their associated plugs from the plug holder. Simultaneously, upon forward movement of the ejector rods, the cam 132 actuates the tubes 130 in the forward direction to assist in the removal of the plugs from the plug holder. The ejector rods 181, 181 extend longitudinally of the wire insertion machine and normally bear against forward extensions 10a of the tray 10 as shown in Fig. 15. When the feed table 42 is in its extreme forward position, the forward extensions 10a of the jig 10 are positioned in openings 180, see Figs. 6 and 15 in the wire insertion machine and engage the ejector rods 181, 181.

Operation of the ejector rods 181, 181 is effected by means of a cam 182 formed, for example, as illustrated in Fig. 22 and fixedly secured to the cam shaft 96. Associated with the cam 182 is an arm 183 carrying a cam follower which is resiliently urged into engagement with the cam 182 by means of a spring 184. The upper end of

the arm 183 is fixedly secured to a shaft 185 extending transversely of the wire insertion machine. Extending upwardly from opposite ends of the shaft 185 are arms 186, 186 which engage a pair of yokes 187, 187 adjustably secured to the ejector rods 181, 181. As the cam 182 is rotated, the lower end of the arm 183 is moved to the right with respect to Fig. 1, thereby pivoting the shaft 185 in the counter-clockwise direction. By this construction, the upper ends of the arms 186 are moved to the left with respect to Fig. 1, thereby forcing the ejector rods 181, 181 forward effecting withdrawal of the plugs from the plug holder. The cam 132 which operates the tube crosshead is so formed that the tubes 130 will be caused to advance simultaneously with the ejector rods 181, 181. By this construction, the rubber plugs and their associated pairs of wires are removed from the plug holder without any danger of the wires slipping with respect to the plugs. Also, if the machine is operating with one or more pairs of wires missing, the perforated plug or plugs will be ejected from the plug holder by the advance stroke of the tubes.

Extending downwardly from the ejector cam follower 183, is a bracket 188, which has its lower end secured to a hinged actuating rod 189. By this construction, as the cam follower 183 is rotated counterclockwise about the shaft 185, the actuating rod 189 is moved to the right with respect to Fig. 1. Actuation of the rod 189 in this direction causes a switch operating member 191 secured to the rod 189 to momentarily close a switch 192. Upon actuation of the switch 192, air under pressure is caused to enter the left hand end of the air cylinder 53 (with respect to Fig. 8) thereby retracting the locking plate 54. This permits the displaceable guide to be easily moved rearwardly with respect to the wire support tray. Forward movement of the guide 15 is prevented by leaf spring latches 15a carried by the guide 15, as shown in Fig. 32. Immediately after actuation of the switch 192, a switch operating member 193 also secured to the rod 189 momentarily closes a switch 194. Actuation of the switch 194 causes air under pressure to be admitted to the right hand end (with respect to Fig. 8) of the air cylinder 73, thereby retracting the feed table 42. The cam 132 which controls operation of the tubes 130 retracts the expander tubes to their original position immediately following the ejection stroke. At the same time, the cam 168 which controls operation of the split funnel plate closes the split funnel plate.

Following retraction of the expander tubes 130, the transfer or lifting plate 88 is raised, thereby positioning a loaded plug holder 44 in alignment with the openings in the split funnel plates. As previously described, before the pairs of wires may be inserted into the plugs a loaded plug holder must be positioned on the transfer plate. By this construction, as the transfer plate is raised, the loaded plug holder on the transfer plate forces the other plug holders upward an amount equal to the height of one plug holder.

Operation of the transfer plate is effected by means of a cam 196 secured to the cam shaft 96, see Fig. 23. Associated with the cam 196 is an arm 197 carrying a cam follower in engagement with the cam 196 as illustrated in Figs. 1 and 23. The arm 197 is secured to a shaft 198 pivotally mounted transversely of the machine and is resiliently biased into engagement with the cam 196, for example, by a spring as indicated at 199. Depending outwardly from the shaft 198 is a pair of arm projections 201, 201 which are pivotally secured to the lower ends of a pair of adjustable links 202, 202 as illustrated in Figs. 1 and 6. The upper ends of the adjustable links are secured to a rod 203 mounted in a transfer plate frame 204. The transfer plate frame, in turn, is slidably mounted in a pair of adjustable vertical ways 205, 205 secured to the frame of the wire insertion machine, for example, by means of bolts 206. Relative horizontal positioning of the vertical ways 205, 205 may

be effected by means of a plurality of adjusting bolts 207 which extend through the frame of the machine and bear against the sides of the vertical ways (see Fig. 28).

Upon clockwise rotation of the cam 196, the arm 197 is pivoted in the clockwise direction about the shaft 198, thereby raising the left hand end of the arm projections 201, 201, which, in turn, elevate the transfer plate frame 204 a predetermined amount as illustrated in Fig. 6. Upon raising the transfer plate 88, the upper corners 15 of the plug holder 44 bear against cam surfaces 211, 211 which are provided on the inner ends of a pair of latches 212, 212. The latches 212, 212 are resiliently mounted for horizontal movement between predetermined limit positions in a plug holder guide 213. The plug holder guide 213 extends transversely of the wire insertion machine and terminates in expanded portions 213a, 213a, at its opposite ends, in which the latches 212, 212 are mounted. The previously described backer-up plate 131 is formed integrally with the central portion of the plug holder guide 213. A pair of springs 214, 214, resiliently urge the forward end of the latches 212, 212 into the path of the plug holders 44. After the plug holders 44 are elevated to a position above the upper edges of the latches 212, 212, the latches are forced inwardly by means 25 of the springs 214, 214, and support the plug holders 44 in their elevated position when the transfer plate 88 is lowered by means of the cam 96. As previously described, the transfer plate 88 is not lowered until after the plugs have been pierced.

Upon positioning a loaded plug holder 44 in front of the split funnel plate 155, a plurality of pairs of needles 215, formed, for example, as illustrated in Figs. 39 to 42, inclusive, are forced forward thereby piercing the rubber plugs positioned in the plug holder. Each pair of needles 215 is mounted in a needle block 216 secured to a needle crosshead 217, as illustrated in Figs. 8 and 19.

Operation of the needle crosshead 217 is effected by means of a cam 218, formed, for example, as illustrated in Fig. 21. The cam 218 has a cam track 219 therein 40 which engages a cam follower 221 carried by an arm 222. As shown in Fig. 1, the arm 222 is secured to a shaft 223 pivotally mounted transversely of the wire insertion machine. Extending upwardly from the shaft 223 are a pair of bifurcated arms 224, 224, which engage 45 a pair of links 225, 225 secured to the needle crosshead 217.

With reference to Figs. 2, 7 and 11, the needle crosshead 217 extends transversely of the wire insertion machine and is slidably mounted on a pair of slides 227 and 228 formed integrally with the tube crosshead 139. The left hand slide 227 is formed, for example, as illustrated in Fig. 7 to prevent relative transverse movement of the needle crosshead 217 with respect to the wire insertion machine. A pair of guides 229, 229, adjustably mounted on longitudinal frame members of the wire insertion machine and adapted to bear against the upper surface of the needle crosshead 217, prevent vertical displacement of the needle crosshead. Relative vertical positioning of the guides 229 is effected by means of 50 a plurality of bolts 231 which extend through the guides 229 and bear against the upper surface of the longitudinal frame members.

Upon clockwise rotation of the cam 218, the lower end of the arm 222 is moved to the right with respect to Fig. 1, thereby pivoting the shaft 223 in a counter-clockwise direction. The upper ends of the bifurcated arms 224 which are secured to the links 225 are moved to the left with respect to Fig. 1, thereby forcing the needle crosshead forward and inserting the needles 215 into the 55 plugs carried in the plug holder.

The pairs of needles 215 are carried by the needle crosshead 217 in axial alignment with the pairs of tubes 130 which are carried by the tube crosshead 139 and the needles 215 are normally positioned interiorly of the tubes 130. The needles 215 are provided with reduced

end portions 215a and terminate in sharp points which are adapted to pierce the plugs. As the reduced end portion 215a of the needles 215 is about to enter the plugs, as shown in Fig. 39, the cam 132 actuates the tube cross-head 139 to the left with respect to Fig. 1, thereby moving the tubes 130 forward at a rate of speed equal to the advance of the needles until both the needles and the plugs have entered their respective guide holes in the split funnel plate 155, as shown in Fig. 41. By this construction, the plugs are transferred from the needles to the tubes as the two continue forward to the ends of their respective strokes. When the needles and tubes are moving forward, the shoulder 215b, formed by the reduced end portion 215a of the needles 215 must be slightly in advance of the ends of the tubes to prevent the tubes from cutting the rubber plugs as they are forced through the plugs. The tubes 130 rest in their advanced position against shoulders 233 formed at the right hand end of the openings in the split funnel plate 155, thereby presenting a continuous unobstructed opening through the split funnel plate and tubes into which the wires may be inserted after the needles are withdrawn.

Simultaneously, upon forward movement of the needles 215, a pair of pusher rods 234, 234 advance and transfer the upper empty plug holder from the wire insertion machine onto a continuously operating conveyor 235. As illustrated in Fig. 8, the push rods 234 are adjustably mounted in brackets 236 extending upwardly from the needle crosshead 217. The forward ends of the push rods 234 are adapted to be projected through openings 237 formed in the upper end of the plug holder guide 213 and push the upper empty plug holder onto the conveyor 235. The conveyor 235 in turn transfers the empty plug holder to a discharge chute or to a second conveyor, not shown, by means of which the empty plug holder is removed from the wire insertion machine. With reference to Fig. 4, the conveyor 235 consists of an endless belt which passes over a plurality of pulleys 235a mounted on the frame of the wire insertion machine and is continuously driven by means of a motor 235b.

The needles are immediately withdrawn at the end of their advanced stroke by means of the above mentioned cam 218 leaving the rubber plugs positioned on the tubes 130. At the same time, the cam 182 operates to retract the ejector rods 181, 181. At the end of the retraction stroke of the ejector rods 181, 181, a switch operating member 238 (see Fig. 1) carried by the actuating rod 189 momentarily closes a switch 239. Actuation of the switch 239 permits air to enter the right hand end of the air cylinder 114 with respect to Fig. 3. Admitting air to the forward or right hand end of the air cylinder 114 pivots the shift lever 115 clockwise about its pivot point 117 as shown in Fig. 3, thereby disengaging the high speed shaft 104 of the gear reducer 105 from the driving pulley 102 and engaging the shaft 104 with the brake 111 as previously described. By this construction, after the ejector rods 181, 181 are retracted, rotation of the cam shaft 96 is stopped. This finishes one complete cycle of operation of the wire insertion machine. After the wire tray 10 supporting the plug and wire assemblies is removed from the machine, a loaded plug holder inserted into the machine, and a second wire tray positioned on the feed table 42, a second operating cycle of the machine may be started by closing the manually operated switches 76 and 95.

As previously described, operation of the tubes, needles, ejector rods, transfer plate and the split funnel plate are controlled by separate cams mounted on the cam shaft 96. By this construction, a synchronization of all of the various operating phases of the machine is obtained.

Figs. 34 to 43 inclusive, illustrate the various steps in the operation of the wire insertion machine which will now be briefly summarized. As was previously described

at the end of a complete cycle of operation of the wire insertion machine, a loaded plug holder is positioned in axial alignment with the openings in the split funnel plate and the plugs in the plug holder have tubes inserted therethrough and are prepared for the reception of wires.

With reference to Fig. 34, when the operator of the machine closes the manually operated switch 76, the feed table is advanced and the wires which are carried by the wire jig are inserted into the tubes 130. The operator of the machine now closes the manually operated switch 95 which causes the cam shaft 96 to make one complete revolution. Upon starting rotation of the cam shaft 96, the tubes 130 are withdrawn from the plugs, thereby transferring the plugs from the tubes to the wires as illustrated in Fig. 35. The split funnel plate 155 is then opened to the position shown in Fig. 17a, and the tubes 130, 130 and ejector rods 181, 181 advance, thereby forcing the wire jig rearwardly with respect to the plug holder and removing the plugs from the plug holder as illustrated in Figs. 36 and 37.

As illustrated in Fig. 38, the tubes 130, 130 are retracted and the transfer plate is raised to position a second loaded plug holder in alignment with the openings in the split funnel plate. The split funnel plate is then closed and the needles 215, 215 advance and begin to pierce the rubber plugs as shown in Fig. 39. Before the needles have entirely pierced the rubber plugs, the tubes are advanced along with the needles as illustrated in Fig. 40, thereby transferring the rubber plugs from the needles to the tubes as shown in Fig. 41. The needles are then withdrawn leaving the tubes in position against the shoulders 233 in the split funnel plate 155 to provide a continuous unobstructed path through the funnel plates into the tubes. This is the position of the various portions of the wire insertion machine at the end of one complete cycle of operation and, as previously described, rotation of the cam shaft 96 is stopped. A loaded plug holder may now be inserted into the wire insertion machine and onto the transfer plate and a second jig supporting a plurality of wires may be positioned on the feed table of the wire insertion machine in order to prepare the machine for a second cycle of operation.

Fig. 46 is a schematic diagram illustrating the electrical and pneumatic controls for the wire insertion machine. All of the double acting air cylinders are controlled by a pair of solenoid operated valves, which admit air to the cylinders. The cylinders and switches illustrated in Fig. 46 are shown in their position at the end of a cycle of operation of the wire insertion machine, and, prior to the positioning of a wire jig carrying a plurality of pairs of wires and a loaded plug holder onto the machine.

As a wire jig is positioned on the wire insertion machine a switch 52 is momentarily closed. The switch 52 actuates a valve assembly 251 by means of a relay assembly 252. The valve assembly 251 is operable to admit air to either the left or right hand end of the air cylinder 53, and closing the switch 52 admits air to the right end of the air cylinder 53, with respect to Fig. 9, thereby bringing the locking plate forward as previously described. The valve assembly 251 consists of a pair of valves 253 and 254 operated by means of a walking beam 255 pivotally mounted at its mid-point and positioned by a pair of solenoids 256 and 257. Relays 258 and 259 energize and deenergize the solenoids 256 and 257. The relays 258 and 259 in turn are actuated by relay coils 262 and 263, respectively.

Closing the switch 52 momentarily completes a circuit to the relay coil 262 and raises the relay 258. Energizing the relay coil 262 breaks a circuit through contacts 264 and 265, and completes a circuit through contacts 266 and 267. Opening the circuit through the contacts 264 and 265 breaks the holding circuit for the relay coil 263 allowing the relay 259 to drop and close the holding circuit for the relay coil 262 through contacts 268 and 269.

and maintain the relay 258 energized after the switch 52 is opened. The holding circuit for the relay 258 is from a buss 272 at one side of the line, through the relay coil 262, then through conductors 273 and 274, contacts 269 and 268, and through a conductor 275 to a buss 276 at the other side of the line. When the relay 258 is in its upper position, the circuit to the solenoid 256 is completed through the buss 272 at one side of the line, conductor 277, contacts 267 and 266, conductor 278, the solenoid 256, and then through a conductor 279 to the buss 276 at the other side of the line.

Energizing the solenoid 256 causes the walking beam 255 to be pivoted about its mid-point in a counter-clockwise direction, thereby opening the valve 253 permitting air to be admitted to the right hand end of the cylinder 53 and closing valve 254 allowing the air in the left hand end of the cylinder 253 to be exhausted to the atmosphere. The locking plate 54 is thereby forced forward locking the tray 10 in position on the feed table 42, and, at the same time, closing the switch 72.

As previously described, after a plug holder 44 supporting a plurality of rubber plugs is properly positioned in the wire insertion machine, the switch 91 will be closed. The switches 72 and 91 are in series with a manually operated switch 76. Closing the manually operated switch 76 energizes a relay assembly 282 similar to the above-mentioned relay assembly 252 which in turn actuates a valve assembly 283 similar to the above-mentioned valve assembly 251, thereby admitting air to the left hand end of the air cylinder 73 which operates to bring the feed table 42 forward and insert the pairs of wires into the preformed rubber plugs. If the wires have not been properly entered into the plugs the operator of the machine may close the manually operated switch 94 which actuates the relay assembly 282 and valve assembly 283 in such a manner as to retract the feed table 42, thereby withdrawing the wires from the plugs.

After the wires have been properly entered into the plugs the operator of the wire insertion machine may close the manually operated switch 95 to complete the wire insertion operation. Closing the manually operated switch 95 energizes a relay assembly 284, similar to the above-mentioned relay assemblies, which in turn actuates a valve assembly 285, similar to the above-mentioned valve assemblies. This causes air under pressure to be admitted to the right hand end of the air cylinder 114, thereby causing the cam shaft 96 to make one complete revolution as previously described. During the operating cycle of the wire insertion machine, the switches 192 and 194 are closed which actuate the relay assemblies 252 and 282 and thus the valve assemblies 251 and 283, respectively, thereby retracting the locking plate and feed table, respectively, as previously described. At the end of the operating cycle of the wire insertion machine, the switch 239 is momentarily closed which energizes the relay assembly 284 and actuates the valve assembly 285, thereby admitting air to the left hand end of the air cylinder 114 to stop rotation of the cam shaft 96. The previously mentioned series connected switches 178 and 179 which are operated during closing of the split funnel plate are in parallel with the switch 239 and when a circuit is completed through them as previously described, rotation of the cam shaft will be stopped.

From the foregoing, it will be observed that the present invention provides a novel wire insertion machine, which is entirely automatic in operation and which will simultaneously insert a plurality of pairs of wires into a plurality of preformed plug closures quickly and uniformly. Furthermore, the present invention provides a novel wire insertion machine which may be used as a single station in a production line for the manufacture of blasting caps or the like, thereby reducing considerably the amount of time and labor needed for the manufacture of such articles.

While certain embodiments of the present invention

have been illustrated and described herein, it is not intended to limit the invention to such disclosures, and changes and modifications may be incorporated and embodied therein within the scope of the following claims:

- 5 I claim:
1. In a machine to insert a plurality of wires simultaneously into a corresponding plurality of preformed plugs, guide means having a plurality of openings extending therethrough for said wires, feed mechanisms at opposite sides of said guide means to position pluralities of wires and plugs at opposite sides respectively of said guide means in axial alignment with the openings therein, a plurality of needles corresponding in number to said wires positioned in axial alignment with said openings, means to actuate said needles as a group to advance and retract said needles with respect to said plugs to pierce the same, a plurality of expander tubes corresponding in number to said needles, means to actuate said tubes as a group in predetermined sequence with said needles to be inserted through the plugs, means to withdraw the needles from the plugs, means operable after withdrawal of the needles to actuate the wire feed mechanism and insert the wires through said guide means and into the tubes, and mechanism to withdraw said tubes from said plugs whereby the plugs are caused to grip the wires.
  2. In a machine to insert a plurality of wires simultaneously into a corresponding plurality of preformed plugs, guide means having a plurality of openings extending therethrough for said wires, feed mechanisms mounted at opposite sides of said guide means to position pluralities of wires and plugs at opposite sides respectively of said guide means in axial alignment with the openings therein, a plurality of needles corresponding in number to said wires positioned in axial alignment with said openings, means to actuate said needles as a group to advance and retract said needles with respect to said plugs to pierce the same, a plurality of expander tubes corresponding in number to said needles in axial alignment with said needles, means to actuate said tubes as a group in predetermined sequence with said needles to be inserted through the plugs, means to withdraw the needles from the plugs, means operable after withdrawal of the needles to actuate the wire feed mechanism and insert the wires through said guide means and into the tubes, and mechanism to withdraw said tubes from said plugs whereby the plugs are caused to grip the wires.
  3. In a machine to insert a plurality of wires simultaneously into a corresponding plurality of preformed plugs, guide means having a plurality of openings extending therethrough for said wires, feed mechanisms mounted at opposite sides of said guide means operable in predetermined sequence to position pluralities of wires and plugs at opposite sides respectively of said guide means in axial alignment with the openings therein, a plurality of needles corresponding in number to said wires positioned in axial alignment with said openings at the opposite side of said guide means from the wires, means to actuate said needles as a group to advance and retract said needles with respect to said plugs to pierce the same, a plurality of expander tubes corresponding in number to said needles closely surrounding said needles, means to actuate said tubes as a group coaxially of the needles in predetermined sequence with said needles to be inserted through the plugs, means to withdraw the needles from the plugs, means operable after withdrawal of the needles to actuate the wire feed mechanism and insert the wires through said guide means and into the tubes, and mechanism to withdraw said tubes from said plugs whereby the plugs are caused to grip the wires.
  4. In a machine to insert a plurality of wires simultaneously into a corresponding plurality of preformed plugs, guide means having a plurality of openings extending therethrough for said wires, feed mechanisms mounted at opposite sides of said guide means to position pluralities of wires and plugs at opposite sides respectively of

axial therewith, means to actuate said tubes as a group to advance and retract in predetermined sequence with said needles to be inserted through the plugs, means to withdraw the needles from the plugs, means operable after withdrawal of the needles to actuate the wire feed mechanism and insert the wires through said guide means and into the tubes, and mechanism to withdraw said tubes from said plugs whereby the plugs are caused to grip the wires.

11. In a machine to insert a plurality of wires simultaneously into a corresponding plurality of preformed plugs, guide means having a plurality of openings extending therethrough for said wires, wire feed mechanism mounted at one side of said guide means operable to position a plurality of pairs of wires at one side of said guide means, plug feed mechanism mounted at the opposite side of said guide means operable to position a plurality of plugs at the opposite side of said guide means from said wires, a plurality of needles corresponding in number to said wires, means to actuate said needles as a group to advance and retract said needles with respect to said plugs to pierce the same, a plurality of expander tubes corresponding in number to said needles closely surrounding said needles, means to actuate said needles and tubes in predetermined sequence to cause the needles to pierce the plugs and then to insert the tubes through the plugs and withdraw the needles from the plugs, means operable after withdrawal of the needles to actuate the wire feed mechanism and insert the wires through said guide means and into the tubes, and mechanism to withdraw said tubes from said plugs whereby the plugs are caused to grip the wires.

12. In a machine to insert a plurality of pairs of wires simultaneously into a corresponding plurality of preformed plugs, guide means having a plurality of openings extending therethrough for said wires, wire feed mechanism mounted at one side of said guide means operable to position a plurality of pairs of wires at one side of said guide means in axial alignment with the openings therein and actuatable to advance said wires and insert the same through the openings, plug feed mechanism mounted at the opposite side of said guide means operable in predetermined sequence to said wire feed mechanism to position a plurality of plugs at the opposite side of said guide means from said wires in axial alignment therewith, a plurality of needles corresponding in number to said wires positioned in axial alignment with said openings at the opposite side of said guide means from the wires, means to actuate said needles as a group to advance and retract said needles with respect to said plugs to pierce the same, a plurality of expander tubes corresponding in number to said needles closely surrounding said needles, means to actuate said needles and tubes in predetermined sequence to cause the needles to pierce the plugs and then to insert the tubes through the plugs and withdraw the needles from the plugs, means operable after withdrawal of the needles to actuate the wire feed mechanism and insert the wires through said guide means and into the tubes, and mechanism to withdraw said tubes from said plugs whereby the plugs are caused to grip the wires.

13. In a machine to insert a plurality of wires simultaneously into a corresponding plurality of preformed plugs, guide means having a plurality of openings extending therethrough for said wires, wire feed mechanism mounted at one side of said guide means operable to position a plurality of pairs of wires at one side of said guide means, plug feed mechanism mounted at the opposite side of said guide means operable to position a plurality of plugs at the opposite side of said guide means from said wires, a plurality of needles corresponding in number to said wires, actuating mechanism for said needles operable to advance and retract said needles as a group with respect to said plugs to pierce the same,

a plurality of expander tubes corresponding in number to said needles and coaxial therewith, actuating mechanism for said expander tubes operable to advance and retract said expander tubes as a group in predetermined sequence with said needles to insert said tubes through the plugs, control means to withdraw the needles from the plugs, means to actuate the wire feed mechanism to insert said wires through said guide means and into the tubes, and mechanism to withdraw said tubes from said plugs whereby the plugs are caused to grip the wires.

14. In a machine to insert a plurality of wires simultaneously into a corresponding plurality of preformed plugs, guide means having a plurality of openings extending therethrough for said wires, wire feed mechanism mounted at one side of said guide means operable to position a plurality of pairs of wires at one side of said guide means, plug feed mechanism mounted at the opposite side of said guide means operable to position a plurality of plugs at the opposite side of said guide means from said wires, a plurality of needles corresponding in number to said wires, actuating mechanism for said needles operable to advance and retract said needles as a group with respect to said plugs to pierce the same, a plurality of expander tubes corresponding in number to said needles and coaxial therewith, actuating mechanism for said expander tubes, control means to actuate said needle actuating mechanism and said tube actuating mechanism to cause the needles to pierce the plugs then insert the tubes through the plugs and withdraw the needles from the plugs, means to actuate the wire feed mechanism to insert said wires through said guide means and into the tubes, and mechanism to withdraw said tubes from said plugs whereby the plugs are caused to grip the wires.

15. In a machine to insert a plurality of pairs of wires simultaneously into a corresponding plurality of preformed plugs, guide means having a plurality of openings extending therethrough for said wires, wire feed mechanism mounted at one side of said guide means operable to position a plurality of pairs of wires at one side of said guide means in axial alignment with the openings therein, plug feed mechanism operable in predetermined sequence with said wire feed mechanism mounted at the opposite side of said guide means to position a plurality of plugs at the opposite side of said guide means from said wires in axial alignment therewith, a plurality of needles corresponding in number to said wires positioned in axial alignment with said openings at the opposite side of said guide means from said wires, actuating mechanism for said needles operable to advance and retract said needles as a group with respect to said plugs to pierce the same, a plurality of expander tubes corresponding in number to said needles and coaxial therewith, actuating mechanism for said expander tubes operable to advance and retract said expander tubes as a group in predetermined sequence with said needles to insert said tubes through the plugs, control means to actuate said needle actuating mechanism and said tube actuating mechanism to cause the needles to pierce the plugs then insert the tubes through the plugs and withdraw the needles from the plugs, means to actuate the wire feed mechanism to insert said wires through said guide means and into the tubes, and mechanism to withdraw said tubes from said plugs whereby the plugs are caused to grip the wires.

16. In a machine to insert a plurality of wires simultaneously into a corresponding plurality of preformed plugs, upper and lower support members mounted for relative movement with respect to each other between predetermined limit positions, a plurality of corresponding downward and upward extensions carried by said upper and lower support members respectively and operable in one limit position of said support members to form a plurality of guide openings through which said wires may be advanced, said extensions operable in the

other limit position of said support members to provide openings through which the plugs may be withdrawn, actuating mechanism for said support members operable to actuate the same to either predetermined limit position, feed mechanisms mounted at opposite sides respectively of said guide openings operable to position pluralities of wires and plugs at opposite sides respectively of said support members in axial alignment with the guide openings therein, a plurality of needles corresponding in number to said wires positioned in axial alignment with said openings and actuatable as a group to advance and retract with respect to said plugs to pierce the same, a plurality of expander tubes corresponding in number to said needles coaxial therewith and actuatable as a group to advance and retract with respect to said plugs to be inserted through said plugs, means to actuate said needles and said tubes in predetermined sequence to cause the needles to pierce the plugs then insert the tubes through the plugs and withdraw the needles from the plugs, means to actuate the wire feed mechanism to insert the wires through said guide openings and into the tubes, and mechanism to withdraw said tubes from said plugs whereby the plugs are caused to grip the wires.

17. In a machine to insert a plurality of wires simultaneously into a corresponding plurality of preformed plugs, upper and lower support members mounted for relative movement with respect to each other between predetermined limit positions, a plurality of corresponding downward and upward extensions carried by said upper and lower support members respectively and operable in one limit position of said support members to form a plurality of guide openings through which said wires may be advanced, said extensions operable in the other limit position of said support members to provide openings through which the plugs may be withdrawn, actuating mechanism for said support members operable to actuate the same to either predetermined limit position, feed mechanisms mounted at opposite sides respectively of said guide openings operable in predetermined sequence to position pluralities of wires and plugs at opposite sides respectively of said support members in axial alignment with the guide openings therein, a plurality of needles corresponding in number to said wires positioned in axial alignment with said openings and actuatable as a group to advance and retract with respect to said plugs to pierce the same, a plurality of expander tubes corresponding in number to said needles closely surrounding each needle and actuatable as a group to advance and retract with respect to said plugs to be inserted through said plugs, means to actuate said needles and said tubes in predetermined sequence to cause the needles to pierce the plugs, then insert the tubes through the plugs and withdraw the needles from the plugs, means to actuate the wire feed mechanism to insert the wires through said guide openings and into the tubes, mechanism to withdraw said tubes from said plugs whereby the plugs are caused to grip the wires, means to actuate said support members to separate said downward and upward extensions to permit the plugs to be drawn between said extensions, and means to actuate said wire feed mechanism to withdraw the wires and the plugs between said downward and upward extensions.

18. In a machine to insert a plurality of pairs of wires simultaneously into a corresponding plurality of preformed plugs, upper and lower support members mounted for relative movement with respect to each other between predetermined limit positions, a plurality of corresponding downward and upward extensions carried by said upper and lower support members respectively and operable in one limit position of said support members to form a plurality of guide openings through which said wires may be advanced, said extensions operable in the other limit position of said support members to provide openings through which the plugs may be withdrawn, actuating means for said support members operable to

actuate the same to either predetermined limit position, wire feed mechanism mounted at one side of said guide openings operable to position a plurality of wires at one side of said support members and actuatable to advance said wires with respect to said support members to insert the wires through said guide openings, a plug holder operable to support a plurality of plugs mounted for sliding movement transversely of said machine, plug feed mechanism mounted at the opposite side of said guide openings operable to position said plug holder at the opposite side of said support members from the wires in alignment with the guide openings therein, a plurality of needles corresponding in number to said wires, actuating mechanism for said needles operable to advance and retract said needles as a group with respect to said plugs to pierce the same, a plurality of expander tubes coaxial with said needles, actuating mechanism for said expander tubes operable to advance and retract said expander tubes as a group in predetermined sequence with said needles, control means to actuate said needle actuating mechanism and said tube actuating mechanism in predetermined sequence to cause the needles to pierce the plugs then insert the tubes through the plugs and withdraw the needles from the plugs, means operable after withdrawal of the needles to actuate the wire feed mechanism to insert the wires through said guide openings and into the tubes, and means to withdraw the tubes from said plugs whereby the wires are caused to grip the plugs.

19. In a machine to insert a plurality of pairs of wires simultaneously into a corresponding plurality of preformed plugs, upper and lower support members mounted for relative horizontal movement with respect to each other between predetermined limit positions, a plurality of corresponding downward and upward extensions carried by said upper and lower support members respectively and operable in one limit position of said support members to form a plurality of guide openings through which said wires may be advanced, said extensions operable in the other limit position of said support members to provide openings through which the plugs may be withdrawn, actuating means for said support members operable to actuate the same to either predetermined limit position, wire feed mechanism mounted at one side of said guide openings operable to position a plurality of wires at one side of said support members in axial alignment with said guide openings and actuatable to advance said wires with respect to said support members to insert the wires through said guide openings, a plug holder mounted for sliding movement transversely of the machine operable to support a plurality of plugs, plug feed mechanism mounted at the opposite side of said guide openings operable to position said plug holder at the opposite side of said support members from the wires in alignment with the guide openings therein, a plurality of needles corresponding in number to said wires positioned in axial alignment with said guide openings at the opposite side of said support members from the wires, actuating mechanism for said needles operable to advance and retract said needles as a group with respect to said plugs to pierce the same, an expander tube closely surrounding each needle, actuating mechanism for said expander tubes operable to advance and retract said expander tubes as a group in predetermined sequence with said needles, control means to actuate said needle actuating mechanism and said tube actuating mechanism in predetermined sequence to cause the needles to pierce the plugs then insert the tubes through the plugs and withdraw the needles from the plugs, means operable after withdrawal of the needles to actuate the wire feed mechanism to insert the wires through said guide openings and into the tubes, means to withdraw the tubes from said plugs whereby the wires are caused to grip the plugs, means to actuate said support member actuating means to separate said downward and upward extensions and provide a space therebetween through which the plugs may be passed, means to actuate said

wire feed mechanism in the reverse direction to withdraw the wires from the plug support and between said downward and upward extensions, and control means operable upon withdrawal of the wire feed mechanism to advance said expander tubes and eject the plugs from the plug holder.

20. In a machine to insert a plurality of wires simultaneously into a corresponding plurality of preformed plugs, guide means having a plurality of guide openings extending therethrough for said wires, shoulders on said guide openings, feed mechanism mounted at opposite sides of said guide means to position pluralities of wires and plugs at opposite sides, respectively, of said guide means in axial alignment with said guide openings, a plurality of needles corresponding in number to said wires positioned in axial alignment with said openings, means to actuate said needles as a group to advance and retract said needles with respect to said plugs to pierce the same, and a plurality of hollow expander tubes corresponding in number to said needles, means to actuate said tubes as a group in predetermined sequence therewith to be inserted through the plugs into engagement with the corresponding guide opening shoulders, said tubes each having an axial opening therethrough substantially equal to the diameter of said guide openings positioned in confronting relation to said guide openings upon engagement of said needles with said shoulders to provide a uniform continuous opening through said guide means and said tubes.

21. In a machine to insert a plurality of wires simultaneously into a corresponding plurality of preformed plugs, guide means having a plurality of openings extending therethrough for said wires, a shoulder on each of said guide openings at one side of said guide means, wire feed mechanism mounted at the opposite side of said guide means operable to position a plurality of pairs of wires at said opposite side of said guide means, plug feed mechanism mounted at said one side of said guide means operable to position a plurality of plugs at said one side of said guide means, a plurality of needles corresponding in number to said wires, means to actuate said needles as a group to advance and retract said needles with respect to said plugs to pierce the same, a plurality of expander tubes corresponding in number to said needles mounted at said one side of said guide means co-axially with said needles, means to actuate said tubes as a group to advance and retract in predetermined sequence with said needles to be inserted through the plugs into engagement with their corresponding guide opening shoulders at said one side of said guide means, said tubes having axial openings therethrough substantially equal to the diameter of said guide openings positioned in confronting relation with said guide openings upon engagement of said tubes with said shoulders to provide a uniform continuous opening through said guide means and said tubes, means to withdraw the needles from the plugs, means operable after withdrawal of said needles to actuate said wire feed mechanism toward said opposite side of said guide means and insert the wires into said uniform continuous opening formed by said guide means and said tube openings, and mechanism to withdraw said tubes from said plugs whereby said plugs are caused to grip said wires.

22. In a machine to insert a plurality of wires simultaneously into a corresponding plurality of preformed plugs, a support table, guide means extending transversely of said support table at substantially the mid-point thereof having a plurality of guide openings extending therethrough for said wires, shoulders on said guide openings, feed mechanism mounted on said support table for movement relative to said guide means at opposite sides of said guide means and operable to position pluralities of wires

and plugs at opposite sides, respectively, of said guide means in axial alignment with said guide openings, a plurality of needles mounted above said table corresponding in number to said wires positioned in axial alignment with said guide openings, means to actuate said needles as a group to advance and retract said needles with respect to said plugs to pierce the same, and a plurality of hollow expander tubes mounted above said table corresponding in number to said needles and co-axial therewith, means to actuate said tubes as a group in predetermined sequence with said needles to be inserted through the plugs into engagement with the corresponding guide opening shoulders, said tubes each having an axial opening therethrough substantially equal to the diameter of said guide openings positioned in confronting relation to said guide openings upon engagement of said needles with said shoulders to provide a uniform continuous opening through said guide means and said tubes.

23. In a machine to insert a plurality of wires simultaneously into a corresponding plurality of preformed plugs, a support table, guide means extending transversely of said support table at substantially the mid-point thereof having a plurality of openings extending therethrough longitudinally of said table for said wires, a shoulder on each of said guide openings at one side of said guide means, a flared mouth portion for said guide openings at the opposite side of said guide means, wire feed mechanism mounted on said table for movement relative to said guide means at said opposite side of said guide means operable to position a plurality of pairs of wires at said opposite side of said guide means, plug feed mechanism mounted on said table for movement relative to said guide means at said one side of said guide means operable to position a plurality of plugs at said one side of said guide means, a plurality of needles mounted above said table corresponding in number to said wires, means to actuate said needles as a group to advance and retract said needles with respect to said plugs to pierce the same, a plurality of expander tubes corresponding in number to said needles mounted above said table at said one side of said guide means co-axially with said needles, means to actuate said tubes as a group to advance and retract said tubes in predetermined sequence with said needles to be inserted through the plugs into engagement with its corresponding guide opening shoulders at said one side of said guide means, said tubes having axial openings therethrough substantially equal to the diameter of said guide openings positioned in confronting relation with said guide openings upon engagement of said tubes with said shoulders to provide uniform continuous openings having flared mouth portions through said guide means and said tubes, means to withdraw the needles from the plugs, means operable after withdrawal of said needles to actuate said wire feed mechanism toward said opposite side of said guide means and insert the wires into said uniform continuous openings formed by said guide means and said tube openings, and mechanism to withdraw said tubes from said plugs whereby said plugs are caused to grip said wires.
